UNITED STATES PATENT OFFICE.

GEORGE PORTEOUS, OF GUELPH, CANADA, ASSIGNOR TO JAMES W. LYON,
OF SAME PLACE.

DESIGN FOR A MUSIC-RACK.

SPECIFICATION forming part of Design No. 22,249, dated February 28, 1893.

Application filed January 9, 1893. Serial No. 457,839. Term of patent 7 years.

To all whom it may concern:

Be it known that I, GEORGE PORTEOUS, a subject of the Queen of Great Britain, residing in the city of Guelph, in the county of 5 Wellington, in the Province of Ontario, Canada, have invented and produced a new and original Design for Music-Racks, of which the following is a specification, reference being had to the accompanying drawing, forming 10 part thereof.

Referring now to the drawing which shows a perspective view of my music rack—A is a lyre-shaped wing connected to side pieces C at about the center thereof, and B is a similarly shaped wing connected to said side pieces 15

near the bottom thereof, which side pieces extend from the floor to a point slightly above the top of the wing A. Behind each wing and between the side pieces C are thin slats D, arranged flatwise between round cross rails E 20 which extend along the ends of said slats and between the side pieces C.

What I claim as new is—

The design for a music-rack, substantially as herein shown and described.

Guelph, December 14, 1892.

GEORGE PORTEOUS.

In presence of—

CHARLES T. LAWRENCE,
DON. GUTHRIE.
